UNITED STATES PATENT OFFICE.

STEVE KULICH, OF NEW YORK, N. Y.

LATCH-RELEASER.

1,254,240.

Specification of Letters Patent. Patented Jan. 22, 1918.

Application filed December 13, 1916. Serial No. 136,718.

To all whom it may concern:

Be it known that I, STEVE KULICH, subject of the Emperor of Austria-Hungary, who has declared his intention of becoming a citizen of the United States, residing at New York city, in the county of New York and State of New York, have invented certain new and useful Improvements in Latch-Releasers, of which the following is a specification.

This invention relates to door openers, and more particularly to means for opening doors to garages and similar structures.

One of the main objects of the invention is to provide door opening means of simple construction and operation which act normally to maintain the door in closed position and may be quickly and easily moved into inoperative position so as to release the door. A further object is to provide simple and efficient means for moving the securing means into inoperative position, such means being adapted to be actuated by the wheels of an automobile or similar vehicle. A further object is to provide means for releasing the securing means manually. Further objects will appear from the detail description.

In the drawings:

Fig. 1 is a front view of a garage with a door securing means constructed in accordance with the invention applied.

Fig. 2 is a top plan view of the same.

Fig. 3 is a central longitudinal vertical sectional view taken through the garage and door securing means.

Fig. 4 is a transverse vertical sectional view taken through the garage inside of the doors.

Fig. 5 is a section through one of the supporting blocks taken substantially on line 5—5 of Fig. 3.

Fig. 6 is a detail sectional view taken substantially on line 6—6 of Fig. 3.

Fig. 7 is a fragmentary sectional view of one of the securing bars and heads.

The garage 1 is provided with a door-way 2 above which is supported a track 3. Two doors 4 are slidably supported on this track by the hangers 5. These doors are of such width that, when in closed position, they completely cover the door opening 2, in the usual manner. Each door 4 is provided, at its upper inner corner, with a vertically extending finger 6. A cable 7 has one end secured to this finger and is passed

over a pulley 8 mounted at the side of the garage, a weight 9 being secured on the other end of the cable. These two weights act normally to move the doors 4 apart so as to uncover the door-way or opening 2.

A rectangular bar 10 is slidably mounted on the inner face of each door 4, near the inner edge thereof, in two securing straps 11. Each of these rods is provided, at its lower end, with an integral head 12, and is normally held in depressed position by an expansion spring 13 which is confined between the upper strap 11 and a collar 14 secured about the rod above the lower strap. The head 11a of each bar is provided, on its inner face, with alternately arranged teeth and recesses, the teeth of one head meshing with those of the other, as at 15 so as to prevent independent vertical movement of the bars.

Head 12 is provided with an axial bore adapted to receive a securing pin 16 formed integral with a locking rod 17. Rod 17 is pivotally secured at its outer end in a U-support or housing 18, as at 19, which is carried by a supporting block 20. Block 20 is provided with a transversely extending slot 21 to permit rocking of the stem 17a of rod 17 about its pivotal axis. Block 20 is further provided with a downwardly extending cylindrical bore 22 in which is mounted a plunger 23 having an enlarged disk-like head 24 the central portion of which is raised, as at 25. The lower end of plunger 23 is bifurcated to receive the stem 17a of the locking rod, which is pivotally secured therein by a pin 26. The lower portion of plunger 23 extends into the slot 21, which is of sufficient width to accommodate the plunger, and an expansion coil spring 27 is mounted about the plunger and confined between the head 24 and the annular shoulder at the lower end of the cylindrical bore 22. This spring acts to normally maintain the plunger 23, and consequently the locking rod 17, in raised position. With the rods 17 in this position, the bars 10 are each secured against lateral movement by means of the fingers 16, thus effectually preventing opening of the doors 4.

In practice, two locking rods are employed and are mounted in parallel spaced relation in a housing 28. The heads 24 are so spaced as to be engaged by the front wheels of an automobile approaching the garage. The weight of the automobile is transmitted

through the front wheels of the vehicle to the heads so as to depress the plungers 23. When the plungers are depressed, the locking rods 17 are rocked downward about their pivotal axes so as to release the bars 10. When the bars 10 are released, the weights 9 act to move the doors toward the sides of the garage so as to open the same, thus rendering it possible to open the garage for entry of an automobile without the necessity of the driver getting out of the machine.

In order that the doors may be opened when the automobile is within the garage, I provide supplemental means for releasing the locking bars 10 from the pins 16. For this purpose a rod 29 is rotatably mounted through one of the doors 4, a suitable knob 30 being provided at each end of this rod. A pinion 31 is secured on rod 29 and meshes with a rack 32 formed integral with one of the locking bars 10. By rotating the rod 29 the two bars 10 may be raised against the action of the expansion springs 13, so as to disengage the heads 12 from the locking pins 16. As soon as the bars have been raised into this position, the weights 9 will act to open the doors in the manner previously described.

While I have described my invention specifically as applied to garage doors, it will be evident that it can be used for many other purposes such as doors and gates of various types. It will be evident that there may be slight changes made in the construction and arrangement of the different parts of my invention without departing from the field and scope of the same, and I intend to include all such variations, as fall within the scope of the appended claims, in this application in which the preferred form only of my invention is disclosed.

What I claim is:—

1. In door securing means, the combination of two oppositely movable doors, a locking bar carried by each door, a rockably mounted securing rod normally engaging said locking bar so as to prevent lateral movement of the door, and means for moving said securing rod into inoperative position.

2. In door securing means, the combination of two oppositely movable doors, a locking bar mounted on each door and provided with a bore in its lower end, a securing rod having a locking pin adapted to normally engage into said bore, means for normally holding said securing rod raised, and means for depressing said rod so as to release the locking bar.

3. In door securing means, the combination of two oppositely movable doors, a locking bar slidably mounted on each door for

vertical movement, means for normally holding said bar in depressed position, a securing rod positioned beneath the locking bar and normally in engagement therewith so as to prevent lateral movement of the door, said securing rod being mounted for rotary movement about a horizontal axis, a plunger pivotally secured to the securing rod between the inner end and the pivotal axis thereof, means for normally holding the plunger in raised position, and manually operative means for raising the locking bars.

4. In door securing means, the combination of two oppositely movable doors, a locking bar slidably mounted on each door for vertical movement and provided with an axially extending bore in its lower end, means for normally holding the bar in depressed position, a securing rod having a pin adapted to engage into the bore of said locking bar and pivotally mounted on a horizontal axis at its outer end, a plunger pivotally secured at its lower end to the said securing bar and provided with an extended head at its upper end, an expansion spring mounted about the plunger and acting to normally hold the same in raised position, means for raising said locking bars so as to disengage the same from said locking pins, and means for moving the doors into open position when the locking bars are released.

5. In a door securing means the combination of two oppositely movable doors, parallel locking bars mounted movably on said doors, means for normally holding said bars in depressed position, a securing rod positioned beneath each locking bar and normally in engagement therewith so as to prevent lateral movement of the door, and means for operating said securing rod to release said locking bar and permit lateral movement of said door.

6. In a door securing means the combination of two oppositely movable doors, a locking bar mounted movably on each door, means for normally holding said bar in depressed position, a pivot member engaged with said locking bar to prevent lateral movement of the door, said means being pivotally mounted, means for normally retaining said pivot member in engagement with said locking bar, and means for moving said pivot means upon its pivot to release said locking bar and permit lateral movement of the door.

In testimony whereof I affix my signature in presence of two witnesses:

STEVE KULICH.
